UNITED STATES PATENT OFFICE.

FRANK RHIND, OF BRIDGEPORT, CONNECTICUT, ASSIGNOR OF ONE-HALF
TO THE BRIDGEPORT BRASS COMPANY, OF SAME PLACE.

DESIGN FOR A LAMP-BODY.

SPECIFICATION forming part of Design No. 30,249, dated February 21, 1899.

Application filed January 18, 1899. Serial No. 702,595. Term of patent 14 years.

To all whom it may concern:

Be it known that I, FRANK RHIND, a citizen of the United States, residing at Bridgeport, Connecticut, have invented and produced a new and original Design for a Lamp-Body, of which the following is a specification.

In the accompanying drawings, Figure I is an elevation of a lamp-body, showing my design. Fig. II is a top plan view of the same. 10 1 designates a generally cylindric upper portion, and 2 a cup-shaped lower portion. These are provided with projecting beads 3 and 4. Projecting from the upper portion 1 is an indented band 5. From the lower portion 2 projects a lug 6, terminating in a cy-

lindric portion which extends above the upper edge of the portion 2 and in front of the indented band 5.

The essential feature of my design is the lamp-body provided with the indented band 20 and the lug terminating in a cylindric portion adjacent to said band.

What I claim is—

The design for a lamp-body herein described and shown.

FRANK RHIND.
